Dec. 1223

Theodore W. Gillagore, of Philadelphia, Pa.
Assignor to Savery & Co. of same place.
Letters Patent No. 1223, dated April 3, 1860.

The schedule referred to in these Letters Patent and making part of the same.

To all whom it may concern.

Be it known that I, Theodore W. Gillagore, of the City of Philadelphia, in the State of Pennsylvania, have invented or produced a new and original design for Fire-dogs, and I do hereby declare that the following is a full and exact description of the same; reference being had to the annexed drawing, making a part of this Specification, and to the letters of reference marked thereon.

For the purpose of nominal distinction, I call this design for a fire-dog the Gothic Pattern. It consists of a Gothic spire supported by two Gothic pillars, so as to produce together the general form and outline shown in the drawing, the whole being ornamented in limitation of carvings, as hereinafter specified, and cast in metal, to serve as the front part of a fire-dog. A being the Gothic spire, and B.B. the two Gothic pillars which support it and form all the lower part of the said fire-dog.

Wls. 1223

The pinnacle A. of the Spire is ornamented with the pendant leaves 1-1. and 2. 2. and also with the Creepers 3-3. as shown in the drawing. The two side edges of the body of the Spire, are ornamented with the creepers 4-4; and the front of the same, with an ornamented pinnacle 5. in bass relief.

The pillars (B.B) each present a three faced base 6. supporting gothic ornamentations, above, of the same three faced character - an open gothic anamulated arch 7. being produced between the bases of the two pillars (B.B) by the lower part of the Spire (A), as shown in the drawing.

What I claim as my invention or production, and desire to secure by letters patent is -

The configuration and ornamentations herein described and set forth, as a new and original design for Fire-dogs.

Witnesses.
